STEERING WHEEL

Howard B. Lubarsky, San Francisco, Calif.

Application January 9, 1958, Serial No. 49,180

Term of patent 14 years

(Cl. D14—30)

Fig. 1 is a front plan view of a steering wheel of my design.

Fig. 2 is a side view of said steering wheel.

Fig. 3 is a rear view of said steering wheel.

Fig. 4 is a cross-sectional view of the steering wheel, the section being taken on the lines 4—4 of Fig. 1.

Fig. 5 is a cross-sectional view of the steering wheel taken along lines 5—5 of Fig. 1.

I claim:

The ornamental design for steering wheel, as shown.
